134,158

DESIGN FOR AN AUTOMOTIVE DUMP WAGON

Robert G. Le Tourneau, Peoria, Ill., assignor to
R. G. Le Tourneau, Inc., Stockton, Calif., a cor-
poration of California

Application August 26, 1942, Serial No. 108,045

Term of patent 14 years

To all whom it may concern:

Be it known that I, Robert G. Le Tourneau, a citizen of the United States, residing at Peoria, in the county of Peoria and State of Illinois, have invented a certain new, original, and ornamental Design for an Automotive Dump Wagon, of which the following is a specification, reference being had to the accompanying drawing, forming a part thereof.

In the drawing:

Figure 1 is a side perspective view of an automotive dump wagon, showing my new design.

Figure 2 is also a side perspective view taken from a somewhat different angle than Fig. 1.

Figure 3 is a perspective view of the automotive dump wagon, looking forwardly from the rear and showing the power unit turned to the right.

The automotive dump wagon presents substantially the same appearance on the opposite side from that disclosed.

I claim:

The ornamental design for an automotive dump wagon, as shown and described.

ROBERT G. LE TOURNEAU.
